UNITED STATES PATENT OFFICE.

HOMER P. CHANDLER, OF MANSFIELD, OHIO, ASSIGNOR TO THE OHIO BRASS COMPANY, OF MANSFIELD, OHIO, A CORPORATION OF NEW JERSEY.

CONDUCTOR SUPPORT.

Application filed September 5, 1922. Serial No. 536,186.

To all whom it may concern:

Be it known that I, HOMER P. CHANDLER, a citizen of the United States of America, residing at Mansfield, in the county of Rich-
5 land and State of Ohio, have invented cer-
tain new and useful Improvements in Con-
ductor Supports, of which the following is
a specification.

My invention relates to supports for con-
10 ductors and has particular reference to that
class of supports by means of which a trolley
conductor is suspended from an overhead
support such as an insulated hanger, etc.

The object of my invention is to produce
15 a simple, economical and reliable device
which is easily and quickly installed.

My invention resides in the construction,
combination and relation of the various
20 parts more fully hereinafter described and
claimed.

In the accompanying drawings:-

Figure 1 is a side view in elevation of my
invention and shown as supporting a trolley
conductor.

25 Fig. 2 is an end view of Fig. 1.

Fig. 3 is a longitudinal sectional view of
Fig. 2 on the line 3—3.

Fig. 4 is a transverse sectional view of
Fig. 1 on the line 4—4.

30 Fig. 5 is a transverse sectional view simi-
ilar to Fig. 4, but with the jaws open ready
to receive a trolley conductor.

Fig. 6 is a sectional view on line 4—4 of
35 Fig. 1 of one of the jaw or clamping mem-
bers.

In the preferred construction embodying
my invention shown in the various figures, I
employ a hanger H provided with a threaded
stud S. Secured to the stud by means of
40 threads 1 is a jaw 2 provided with a head 3
and means 4 at the lower end for engaging
the trolley conductor 5. In combination
with the jaw 2 is a jaw 6 also provided with
means 7 to cooperate with the means 4 for
45 gripping the conductor 5. The jaw 6 is also
provided with an integrally formed annular
collar 8 surrounding the head 3 and pro-
vided with the external threads 9. The two
jaw members are held in assembled position
50 by forming a recess 10 in the collar 8 and by
rolling or peening over the upper edge of the
head 3 so as to form the annular lip 11 which
overlaps the collar 8 limiting the movement
of the jaw 6 relative to the jaw 2 in one direc-
55 tion and preventing the separation of the

parts in this direction. Mounted upon the
collar 8 is an operating member 12 having
threads to cooperate with the threads 9 and
a projecting bead 13 which engages with the
projecting member 14 on the jaw 2. Either
60 the collar 8 or the bead 13 will prevent the
separation of the jaws depending on which
one of these elements, 8 or 13, engages with
the member 14. It will be noted that the
two jaws have, when assembled, a limited
65 vertical or longitudinal movement.

As the member 6 is arranged to contact
and cooperate with the lower face of the
hanger H and to pivot thereon, I prefer to
form the upper face of the collar 8 with an
70 arcuate contour as shown in Fig. 6, although
this is not necessary in the operation of my
device.

In the installation of my device I prefer
to mount the hanger H in position first and
75 then secure the clamping device to the
hanger H by rotating the clamping device
in engagement with the stud S until the up-
per face of the head 3 engages with the
lower face of the hanger H. If, when this
80 engagement takes place, the means 4 and 7
are not in alinement with the trolley wire,
the clamping device is then rotated suffi-
ciently in the opposite direction to bring the
means 4 and 7 into alinement with the trolley
85 wire. To now bring the jaws into clamp-
ing engagement with the trolley conductor
the operating member 12 is rotated until the
bead 13 engages with the projecting member
14. When this engagement takes place fur-
90 ther rotation of the operating member 12 in
the same direction will cause the jaw 6 to
rise until some portion of the upper face of
the collar 8 engages with the lower face of
the hanger H. If the trolley wire 5 is suffi-
95 ciently large, the point of engagement is
likely to be the left hand corner L of the
collar 8 and especially so if the top surface
of the collar 8 is left flat instead of being
curved as shown in Fig. 6. If the upper face
100 is curved as shown in Fig. 6 the contact may
take place at various points along the upper
surface, depending upon the size of the trolley
wire. It will usually be found that when
the collar 8 is brought into contact with the
105 lower face of the hanger H that the mem-
bers 4 and 7 of the jaws 2 and 6, respectively,
will be in slight engagement with the con-
ductor 5. If the rotation of the operating
member 12 is conducted and in the same di-
110

rection as previously, the jaw 6 will then be moved toward the jaw 2 about the point of contact between the collar 8 and the hanger H as a fulcrum, and the conductor held in 5 strong engagement between the members 4 and 7.

It will be seen by an inspection of Fig. 5 that my device will still operate and in 10 a similar manner just described, should the jaw 2 be secured to the hanger H, but in such a manner that the upper surface of the head 3 should rest a considerable distance below the lower surface of the hanger H. In that case the collar 8 would be moved 15 upward as the operating member 12 was rotated until the collar 8 engaged with the annular lip 11 at the point K and further rotation of the member 12 would cause the jaw 6 to pivot about its engagement with the jaw 11 at the point K, thereby forcing the jaws into secure engagement 20 with the conductor 5.

There are, of course, many modifications which might be made from that herein described and which would be obvious to one skilled in the art, and which modifications would fall within the scope of my invention, therefore, I do not wish to be limited otherwise than by my claims.

30 I claim:

1. The combination with a support of a conductor clamp comprising a jaw member detachably secured to the support and having means to engage the conductor, a second 35 jaw member having means to engage the conductor opposite to that of the first jaw, means on the second jaw movable relative thereto, means on the first jaw to be engaged by the means on the second jaw whereby 40 the second jaw will be raised into a fulcrum engagement with the support and the conductor engaging means moved into clamping engagement with the conductor when the relative movable means on the second 45 jaw is moved relative thereto.

2. The combination with a support of a conductor clamp comprising a jaw member secured to the support and having means to engage the conductor, a second jaw having 50 a fulcrum engagement with the support and having means to engage the conductor and means rotatably mounted on the second jaw to coact with the first jaw to move the second jaw about its fulcrum point of engagement with the support and into clamping engagement with the conductor.

3. The combination with a support of a conductor clamp comprising a jaw member secured to the support and having means 55 to engage the conductor, a second jaw having a fulcrum engagement with the support and having means to engage the conductor and means mounted on the second jaw and movable longitudinally thereto to coact with the first jaw to move the second jaw about

its fulcrum point of engagement with the support and into clamping engagement with the conductor.

4. The combination with a support of a conductor clamp comprising a jaw member 70 secured to the support and having means to engage the conductor, a second jaw having a fulcrum engagement with the support and having means to engage the conductor and means mounted on the second jaw to rotate thereon and move longitudinally thereto and to coact with the first jaw to move the second jaw about its fulcrum point of engagement with the support and into clamping engagement with the conductor. 75

5. The combination with a support of a conductor clamp comprising a jaw member 80 secured to the support and having means to engage the conductor, a second jaw movable relative to the first jaw and having means to engage the conductor, means on the second jaw and movable relative thereto to move the second jaw first into a fulcrum engagement with the support and then into a clamping engagement with the conductor. 85

6. The combination with a support of a conductor clamp comprising a pair of jaws having means to engage and grip the conductor, means on one jaw to coact with means on the support to secure the clamp to the support, means on the other jaw to engage the support and fulcrum about the point of contact and means on one of the jaws to move the said jaw about its fulcrum engagement with the support and into 90 clamping engagement with the conductor. 95

7. The combination with a support of a conductor clamp comprising a pair of jaws having means to engage and grip the conductor, means on one jaw to coact with means on the support to secure the clamp to the support, means on the other jaw to engage the support and fulcrum about the point of contact and means on one of the jaws to move the said jaw first into fulcrum 100 engagement with the support and then about said fulcrum point and into gripping engagement with the conductor. 110

8. The combination with a support of a conductor clamp comprising a pair of clamping jaws, one jaw having means provided with threads engaging threads on the support to secure the clamp to the support, the other jaw having means encircling the first means and engaging the support in pivotal 115 relation thereto and means to move the second jaw about its pivotal point and into gripping engagement with the conductor. 120

9. The combination with a support of a conductor clamp comprising a pair of clamping jaws, one jaw having means to secure the clamp to the support in substantially rigid relation thereto, the other jaw having means to engage and fulcrum on the support and means for moving the second 130

jaw about its point of engagement with the support to move the jaws into clamping engagement with the conductor.

10. The combination with a support of a conductor clamp comprising a jaw secured to the support and having means to engage the conductor, a jaw coacting with the first jaw to engage and grip the conductor and movable longitudinally of the first jaw and means to move the second jaw longitudinally and into engagement with the support and gripping engagement with the conductor.

11. The combination with a support of a conductor clamp comprising a jaw secured to the support and having means to engage the conductor, a second jaw movable longitudinally of the first jaw and having means to engage the support and coact with the first jaw to grip the conductor and means on the second jaw to engage means located on the first jaw to move the second jaw longitudinally and into engagement with the support and into gripping engagement with the conductor.

12. A conductor clamp comprising a jaw having a head and means to engage a conductor, means on the head to secure the clamp to a support, a second jaw having a collar encircling the head and having means to engage the conductor, and means rotatably mounted on the collar for moving the second jaw into clamping engagement with the conductor.

13. The combination with a support of a conductor clamp comprising a pair of jaw

members each having means coacting to grip the conductor, one jaw having means to engage means on the support to secure the clamp to the support, the other jaw having means provided with an arcuate surface to engage the support and movable about said arcuate surface of contact and means to move the second jaw about said arcuate surface and into clamping engagement with the conductor.

14. A conductor clamp comprising a pair of longitudinally and pivotally movable clamping jaws, means on each jaw to engage the conductor, supporting means on one jaw to secure the clamp to a support, means on the other jaw encircling the supporting means, means on the supporting means coacting with the encircling means to limit the relative longitudinal movement of the jaws in one direction and means on one of the jaws coacting with means on the other jaw to move the jaws relative to each other into clamping engagement on the conductor.

15. The combination with a support of a conductor clamp comprising a pair of jaws to grip the conductor, one jaw being secured to the support and the other jaw having a pivotal contact with the support and means to move the latter jaw about its pivotal point and into clamping engagement with the conductor.

In testimony whereof I affix my signature.

HOMER P. CHANDLER.
